UNITED STATES PATENT OFFICE.

EUGENE EGGLESTON, OF DERBY, OHIO, ASSIGNOR TO GEORGE M. FINCKEL,
OF COLUMBUS, OHIO.

MACHINE FOR WEAVING CROSS-WIRES IN FENCES.

SPECIFICATION forming part of Letters Patent No. 683,685, dated October 1, 1901.

Application filed March 26, 1900. Serial No. 10,238. (No model.)

To all whom it may concern:

Be it known that I, EUGENE EGGLESTON, a citizen of the United States, residing at Derby, in the county of Pickaway and State of Ohio, have invented certain new and useful Improvements in Machines for Weaving Cross-Wires in Fences; and I do hereby declare the following to be a full, clear, and exact description of the invention, such as will enable others skilled in the art to which it appertains to make and use the same.

The primary object of this invention is to provide a machine in which the work of putting on the vertical cross-wires is facilitated and in the use of which the machine and the wire shall not be unduly strained when the machine is drawn away from the fence to pay off the spool or cross-wire to make the span to the next strand-wire.

20 The invention resides in the parts and combination of parts pointed out in the claims.

In the accompanying drawings, illustrating an embodiment of my invention, Figure 1 is a view of a portion of a wire fence, showing my machine in position for weaving or twisting on a cross-wire. Fig. 2 is a perspective view of a fraction of the shifting frame. Fig. 3 is a top plan view of the machine on a larger scale than that employed in Fig. 1, the master-wheel being in section and a portion of the frame being broken out. Fig. 4 is a perspective view of the slide or block that moves in the shifting frame, and Fig. 5 is an end view of the twisting-tube and the pinion or gear thereon that meshes with the master-wheel.

The shifting frame 1 is shown to be constructed of two parallel angle-bars 2, connected by bolts 3'. The outwardly-projecting webs 3 of the angle-bars 2 are each made with notches or recesses 4, arranged at intervals, to engage the horizontal strands 5 of the fence. When the shifting frame has been placed on the fence, it is there retained, but so as to be slidable horizontally, by a rod 6, passed through eyes or staples 7 beyond the inner ends of the notches 4. The slide 8 is shown to have grooved or recessed edges 8^a to fit upon the wings or webs 3^a of the bars 2. 50 Hinged or pivoted, as indicated at 9^a, to this slide 8 is one end of an arm 9, while the other

end of said arm is in like manner hinged or pivotally connected, as indicated at 10, to the extremities of yoke-arms 11, that are rigidly secured to or formed with the lateral extension 12 of the main weaver-frame 12^a. The purpose of this double hinge connection between the slide and the frame carrying the twisting apparatus is to permit that apparatus to be turned while the twister-head is still on the strand-wire, so that it shall stand at or approximately at right angles to that wire, and therefore allow the drawing of the wire in a more nearly direct line out of the twister-head when the machine is pulled off the strand-wire. This direct passage of the wire from the twister-head prevents to a large extent the bending of the wire around the pin 22^a in the twister-head, as would be the case were there no hinge at 10, and therefore avoids injury to the wire and makes the pull easier. The arm 9, as well as other parts of the machine, can obviously be made in a single piece or of two or more pieces joined together and of various shapes. The extension 12 of the weaver-frame also has the bearing or boxing 13 for the weaver-tube. The arms or bars 11 are formed with stop lugs or projections 15, that are adapted to engage the arm 9 or a lug 16 thereon when the machine is swung outwardly from the fence to limit the movement of the machine with respect to the arm 9.

The weaver-tube 18 has on its inner end a flange 19, and said tube is journaled in the bearing or boxing 13. The other end of this weaver-tube protrudes through the outer end of the boxing or bearing and has keyed or fastened to it the pinion 20, that is engaged by the master-wheel 24. The pinion 20, the weaver-tube boxing or bearing, the weaver-tube itself, and its flange 19 are all made with a radial opening, as indicated at 17 and 21 in Fig. 5. A clip 22, open at one side and formed with flaring guiding-lips, is secured on the projecting end of the weaver-tube by a pin 22^a, that passes through both the clip and the weaver-tube. The flange 19 and the pin 22^a keep both the weaver-tube and the gear 20 in place. The flange is furnished with a pin 28 to receive a spool or coil of wire 29. (See Fig. 1.) The end of the frame 12 opposite

that containing the boxing or bearing 13 is furnished with a handle 12^b. A stud or pin 23 on the frame 12 supports the toothed master-wheel 24, that engages the pinion 20, as before stated. This master-wheel is provided with a crank-handle 25, by which the master-wheel is turned. The diameter of the master-wheel is preferably, approximately, three times that of the pinion 20, so that one revolution of the master-wheel works three revolutions of the pinion, and hence makes three coils of the cross-wire. The rim of the wheel 24 is made with a recess to be engaged by the end 26 of a lever 27, fulcrumed on the handle 12^b. The lever 27 has a spring to automatically depress into and normally hold the pin or end 26 in the said recess. This recess is so located that when the end 26 engages it the openings 17 and 21 coincide.

20 In practice the free end of the wire from the coil 29 is threaded through the opening between the pin 22^a and the closed side of the tube 18, (see Fig. 5,) and after securing this free end to the first strand-wire the wire is paid off until the next one is reached and the weaver or twister can be placed on it. The machine is then swung so as to bring the master-wheel in a plane parallel to the plane of the strand-wires or so that the strand-wire 25 in the twister-tube shall stand parallel to the axis of said tube, when upon rotating the master-wheel the cross-wire will be twisted or coiled about the strand-wire. The pin 22^a affords the necessary purchase for the coiling 30 of the wire about the strand-wire. The coil may be either right-hand or left-hand, according to the direction in which the master-wheel is turned, it being practicable to turn the master-wheel in either direction. Three 35 coilings of the cross-wire around any strand are usually sufficient. When one revolution of the master-wheel has been made, the machine is turned outward on the pivot or hinge 10 until the stop 15 abuts against the arm 9 or the stop 16 thereon. This stop is preferably so placed as to limit the outward turning of the machine when it reaches a position substantially at right angles to the strand-wire, in which position the machine can be 40 most easily drawn out to pay off wire from the coil or spool. When the machine is so drawn out, it will be observed that it swings on the hinge connecting the arm 9 with the slide 8. The wire may be paid out as far as desired 45 within the limit permitted by the arm 9, and this is abundant to enable the machine to be moved to and placed upon the next strand-wire. If the space between the strand-wires varies, (and it usually does,) practice enables

the operator to correctly judge the proper extent of the outward swinging of the machine. 60

The advantage of doubly hinging the twisting apparatus to the slide or carriage 8, it will be gathered, resides in the fact that the wire from the spool or bobbin is not pulled around 65 the pin 22^a, thereby avoiding great friction and injury to the wire incident to machines as heretofore placed upon the market. In my machine the wire is pulled directly through the cavity of the twisting-tube or in a direction 70 practically parallel to the axis of that tube.

I do not limit myself to the precise form of the parts shown, as some modifications can obviously be made without departing from 75 the scope of the invention.

What I claim, and desire to secure by Letters Patent, is—

1. A machine for twisting cross-wires onto strand-wires of fences, comprising a weaver-frame, a slotted-tube boxing or casing and a handle portion thereon, a slotted weaver-tube journaled in said casing, a wire-carrying pin projecting as described from the tube, a slotted pinion on said tube, a gear-wheel journaled 80 on said weaver-frame and gearing with said pinion, the gear-wheel having a handle projection, yoke-arms having corresponding ends connected with said weaver-frame and extending on opposite sides of said pinion, a 85 block having a sliding support, and means jointedly connected at one end with the block and at the other end with the yoke-arms.

2. In a machine for twisting cross-wires onto strand-wires, the combination of a frame, 95 a twisting device therein through which the wire is passed to be twisted, and means for operating the same, a slide or carriage, and a double hinge connection between the frame and the carriage, substantially as described. 100

3. In a machine for twisting cross-wires onto strand-wires, the combination of a frame, a twisting device therein through which the wire is passed to be twisted, and means for operating the same, a slide or carriage, means 105 connecting the slide and frame, said means being hingedly connected both to the slide and to the frame, and a stop for limiting the movement of the frame on the means for connecting the slide and the frame, substantially 110 as described.

In testimony whereof I affix my signature in presence of two witnesses.

EUGENE EGGLESTON.
